Des. 190,582
Patented June 13, 1961

190,582

SCREW-ON CAP CONNECTOR

William G. Schinske, Sycamore, Ill., assignor to Ideal Industries, Inc., Sycamore, Ill., a corporation of Delaware

Filed July 12, 1960, Ser. No. 61,321

Term of patent 14 years

(Cl. D26—1)

FIG. 1.

FIG. 2.

FIG. 3.

I claim:

The ornamental design for a screw-on cap connector, as shown.
